(57) **CLAIM**

The ornamental design for a pet leash, as shown and described.

DESCRIPTION

FIG. 1 is a perspective view of a pet leash showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a perspective view of the pet leash of FIG. 1, in an alternate state of the leash being pulled out.

The broken lines in the figures illustrate portions of the pet leash that form no part of the claimed design.
